CLOSURE CAP FOR CONTAINERS

Warren N. Martin, Prairie Village, Kans.

Application September 6, 1955, Serial No. 532,431

8 Claims. (Cl. 215—43)

This invention relates to containers and closures therefor and, more particularly, to an improved form of bottle and safety cap therefor.

In my co-pending application Serial No. 488,587 entitled Container Closure and filed February 16, 1955, now Patent No. 2,752,060, there are pointed out a number of the reasons why it is desirable to provide containers having closure caps adapted for removal only by adults intentionally applying a special technique in the manipulation of the package to remove the cap from the container. Especially notable among these reasons for providing safety caps upon containers is to prevent the removal of same by children who might be injured through access to the contents of the container.

The present invention is concerned with an improvement of different and distinct nature from that disclosed in my aforesaid co-pending application, although intended for the accomplishment of the same broad objectives.

More specifically, it is the most important object of this invention to provide safety containers and cap structure wherein are means for releasably locking the cap upon the container, not only against ultimate removal of the cap from the container, but also against any retrograde screwing of the cap from a fully seated position upon the container. The desirability of this feature will be obvious as it applies to containers for liquid materials, such as many poisons, where it is desirable to prevent breaking the closing seal upon the container except through the intentional manipulations of the structure by an adult.

Another important object of the invention is to provide a safety container and cap structure which are of nature resistant to the effects of vibration, jarring or the like during shipping or transportation and which will remain fully closed and sealed despite subjection to such forces.

Many other important objects of the invention, including important details of construction, will be made clear or become apparent as the following description of the invention progresses.

In the accompanying drawings:

Figure 1 is a fragmentary elevational view of a container made in accordance with the invention and having a safety cap made in accordance with the invention shown in cross-section in fully seated disposition thereon;

Fig. 2 is a cross-sectional view taken on line II—II of Fig. 1;

Fig. 3 is a cross-sectional view taken on line III—III of Fig. 1;

Fig. 4 is a view similar to that of Fig. 1 showing a modified form of container and cap; and

Fig. 5 is a cross-sectional view taken on line V—V of Fig. 4.

Referring now first to Figs. 1, 2 and 3, a container designated 10 is shown for purposes of illustration in the form of an ordinary glass bottle such as might be utilized for the packaging of various medicines and other materials. Container 10 is provided with a sub-

2

stantially cylindrical neck portion 12 having a set of external threads 14 formed thereon, the extremity of neck portion 12 being open at 16. Formed upon neck portion 12 below threads 14 are a pair of opposed projections generally designated 18 and 20 each having a face 22 extending substantially radially from portion 12 of container 10 and a sloped surface 24 extending from the outermost extremity of the face 22 into the neck portion 12 substantially tangential to the curvature of the latter.

A safety cap as contemplated by the invention is formed of resilient material and generally designated 30. Cap 30 is of generally cylindrical or slightly frustoconical configuration having a top wall 32 and a side wall 34, the latter preferably being flared out as at 38 adjacent its open, normally lowermost extremity. Side wall 34 is provided with internally extending structure presenting internal threads 36 operably engageable with external threads 14 of container portion 12. Side wall 34 is also provided below the thread portions 36 thereof with other inwardly extending structure presenting an opposed pair of sets generally designated 40 and 42 of sawtooth-like teeth. Although each set 40 and 42 could conceivably include only a single tooth 44, it is to be preferred that each of sets 40 and 42 include several teeth 44 in adjacent relationship to provide for locking of the cap 30 upon the container 10 with various degrees of tightening of the cap 30 upon screws 14 such as may be required as wear occurs upon a conventional sealing gasket 46 disposed within cap 30 adjacent top wall 32 thereof for effecting a fluid-tight seal between the cap 30 and the container 10 when the cap 30 is fully screwed upon the container 10.

Each of teeth 44 includes a face 48 disposed substantially radially to the axis of container portion 12 when the cap 30 is on container 10 and a sloped surface 50 extending from the innermost extremity of the face 48 of such tooth 44 to the inner surface of side wall 34 or the outermost extremity of an adjacent tooth 44, as the case may be.

Referring now particularly to Fig. 2 the interengagement between the radial face 22 of each of projections 18 and 20 and the radial face 48 of a corresponding tooth 44 of the corresponding set 40 and 42 thereof when the cap 30 is fully screwed upon the container 10 will be evident. It will also be understood that during screwing of the cap 30 onto the container 10, by virtue of the resilient nature of cap 30, the side wall 34 will deform sufficiently to permit the sliding of the surfaces 50 of teeth 44 over the surfaces 24 of the projections 18 and 20 until the cap 30 is rotated to its fully seated position. When in such condition, it will be apparent that the interlocking engagement between faces 48 and 22 prevents retrograde rotation of the cap 30 on container 10 and, therefore, retains the same in a closed, sealed condition until force is oppositely applied to the side wall 34 as indicated by the arrows 52 and 54 in Fig. 2 to deform the side wall 34 of cap 30 from its normal configuration to the configuration illustrated in dotted lines.

When the side wall 34 of cap 30 has been so deformed to the dotted line condition, it will be clear that the teeth 44 are moved outwardly a distance sufficient to clear the projections 18 and 20. Accordingly, the removal of the cap 30 from the container 10 involves the application of squeezing force as at 52 and 54 and the simultaneous retrograde rotation of cap 30 to unthread the threaded portions 36 of cap 30 from the threads 14 of container 10 until the teeth 44 will clear the projections 18 and 20 whereupon the removal of the cap 30 may be completed by continuing the retrograde rotation to completely unthread the cap from the threads 14. The flaring as at 38 of side wall 34 of cap 30 disposes

the teeth 44 in such manner that the distance therebetween is sufficient to clear threads 14, once the teeth 44 are disengaged from projections 18 and 20.

It may be observed that, although the above described action for removing the cap 30 from the container 10 is quite simple and relatively convenient once the technique is known, the possibility of removal of the cap 30 from container 10 by a small child is remote. Similarly the probability of inadvertent removal of the cap 30 from container 10 by an adult, as at night in the dark, is unlikely.

Referring now more particularly to Figs. 4 and 5, wherein is illustrated a modified form of the invention, a container 110 provided with a generally cylindrical neck portion 112 having a set of external, double threads 114 and 115 thereon is shown. Container 110 is also provided with a pair of opposed projections 118 and 120, which are similar to projections 18 and 20 above described but are disposed between the lowermost turns of threads 114 and 115, as best shown in Fig. 4.

The safety cap contemplated by the modified form of the invention is designated 130 and includes a top wall 132 and a side wall 134 formed of resilient material, the latter having an inturned shoulder portion 135 adjacent top wall 132 for accommodating the uppermost extremity of container portion 112 to center the cap 130 thereon. A gasket designated 146 may be provided within cap 130 adjacent top wall 132.

Cap 130 is also provided with internally extending structure in the form of two opposed sets of teeth generally designated 140 and 142, which are in all respects similar to sets 40 and 42 of teeth 44 described in connection with the first form of the invention. The individual teeth of sets 140 and 142 are indicated by the numeral 144 and are each provided with a radial face and a sloping surface respectively similar to faces 48 and surfaces 50 of teeth 44.

In the operation of the modified form of the invention, the sets 140 and 142 of teeth 144 are themselves operably engageable with the threads 114 and 115 of container 110 so as to move downwardly between the latter as the cap 130 is rotated upon the container 110. As rotation of cap 130 is continued the sets 140 and 142 of teeth 144 advance downwardly between the threads 114 and 115 until a tooth 144 of each of sets 140 and 142 is engaged in locked condition with a corresponding projection 118 or 120 on the container 110.

It may be noted that the inner diameter of the cap 130 adjacent the open end thereof as at 138 is substantially greater than the outer diameter of the threads 114 and 115, so that squeezing force may be oppositely applied to the side wall 134 of cap 130 to distort the same for moving the teeth 144 clear of the projections 118 and 120 to permit removal of the cap 130 from the container 110.

It will now be manifest that both of the illustrated embodiments of the invention are ideally adapted for the accomplishment of its above mentioned objectives. It will be equally evident, however, that certain minor modifications or changes could be made from the exact structures shown and described for purposes of illustration without departing from the true spirit and intention of the invention. Accordingly, it is to be understood that the invention shall be deemed limited only by the scope of the appended claims.

Having thus described the invention what is claimed as new and desired to be secured by Letters Patent is:

1. Packaging means comprising a container having a substantially cylindrical portion open at one extremity thereof and provided with external threads; a reusable hollow closure cap of resilient material for said container adapted to fit over said one extremity of the latter and provided with internally extending structure of which at least a portion is adapted for threading engagement with said threads of the container; and a single pair only of opposed, external projections on the container engageable with opposed parts of said structure to prevent retrograde rotation of the cap upon the container when the cap is fully screwed upon said threads of the container, each projection having a face substantially radial to said portion of the container and a surface substantially tangent to the curvature of said portion of the container extending from the outermost extremity of said face, said cap being distortable without breaking from its normal configuration upon application of squeezing force thereto to a temporary configuration disposing said parts of said structure a greater distance apart than the distance between the outermost extremities of said projections, whereby the cap may then be rotated upon the container in a retrograde direction for removal therefrom.

2. In the packaging means as set forth in claim 1, wherein said parts of said structure each have a face substantially radial to said portion of the container when the cap is on the latter and a sloped surface extending from the outermost extremity of said face.

3. In the packaging means as set forth in claim 2, wherein said projections each have a face substantially radial to said portion of the container and a surface substantially tangent to the curvature of said portion of the container extending from the outermost extremity of said last-mentioned face, said faces of said parts of the structure being engageable with said faces of said projections when the cap is fully screwed upon the container.

4. In the packaging means as set forth in claim 2, wherein said structure includes, besides said parts thereof, a set of internal threads operably engageable with said threads of the container.

5. In the packaging means as set forth in claim 2, wherein said parts of said structure constitute the whole thereof and are themselves operably engageable with said threads of the container.

6. In the packaging means as set forth in claim 2, wherein said parts of said structure are spaced apart a distance sufficient to clear said external threads on the container.

7. In the packaging means as set forth in claim 1, wherein said opposed parts of the structure each comprises a series of aligned, similarly facing teeth each having a face substantially radial to said portion of the container when the cap is on the latter and a sloped surface extending inwardly from the outermost extremity of said face.

8. In the packaging means as set forth in claim 7, wherein said projections each have a face substantially radial to said portion of the container and a surface substantially tangent to the curvature of said portion of the container extending from the outermost extremity of said face.
